ENGINE SAFETY SWITCH

Lewis W. Maddox, Clarksville, Ga., assignor of
one-half to Clyde Owen, Atlanta, Ga.

Application January 20, 1948, Serial No. 3,222

1 Claim. (Cl. 200—81.9)

1

This invention relates to engine safety devices, and more particularly to an oil pressure controlled automatic switch for controlling the ignition of an internal combustion engine.

It is well-known that an internal combustion engine requires a predetermined amount of lubrication of the pistons and cylinders, bearings and other working parts, or the cylinders become scorched, the bearings burn out and other damage is caused to the engine. Despite the wide knowledge of this fact, it is not uncommon for an operator to neglect checking and refilling or replacing the oil in his engine.

Therefore it is an object of the present invention to provide a safety device for an engine that will positively indicate a dangerous condition of the oil in the engine.

It is another object of the invention to provide an engine safety device that is operated by the oil pressure of the engine.

It is still another object of the invention to provide an oil pressure operated engine safety device that controls the ignition of the engine.

It is a further object of the invention to provide an engine safety device having simplicity of design, economy of construction and efficiency of operation.

The novel features that are considered characteristic of the invention are set forth with particularity in the appended claim. The invention itself, however, both as to its organization and its method of operation, together with additional objects and advantages thereof, will best be understood from the following description of a specific embodiment when read in connection with the accompanying drawing in which an engine system is diagrammatically illustrated and the safety device of the present invention is shown in cross-section.

Referring now to the drawing, an internal combustion engine system is diagrammatically illustrated as comprising an engine block B containing the cylinders, pistons and crankcase, spark plugs P on the block B for firing the cylinders, a distributor D connected to the plugs P by lines L, a coil C connected by a wire X to the distributor D and receiving power by a wire Y from a battery or generator G. The cylinders and bearings in the crankcase are lubricated by oil supplied under pressure from an oil pressure system O through a supply pipe S and withdrawn or exhausted from the block B through the pipe E back to the pressure system O. The engine system set forth in the foregoing description is of conventional design and forms no part of the present invention per se.

2

According to the present invention, a safety device 1 is installed in the oil supply line S which feeds oil under pressure from the pressure system O to the engine B, or any other line containing oil under pressure, and this safety device 1 is connected with the coil C to control the ignition system of the engine B. Specifically, the safety device 1 comprises a vertically disposed housing 2, preferably tubular, having plugs 3 and 4 connecting it with the supply line S at the bottom and top, respectively. The plugs 3 and 4 have passages 5 and 6 extending axially therethrough for communication between the pipes forming the line S and the chamber 7 within the housing 2.

15 The housing 2 has diametrically disposed openings 8 and 9 extending through its walls, a short distance above the bottom plug 3, to receive insulating sleeves 10 and 11. Electric wires, or other suitable contacts, 12 and 13 extend through the insulating sleeves 10 and 11 and into the chamber 7 in spaced relationship. The wire or contact 12 is connected by a cable 14 with the coil C and the wire or contact 13 is connected by a cable 15 with a ground 16 which may be any grounded portion 20 of the engine system such as the supply line S.

25 A ball or other suitable conducting member 17 is freely positioned in the chamber 7. The ball 17 should be of a size that is sufficient to substantially close the passage 5 and to span the distance between the spaced contacts 12 and 13. The top plug 4 has a nozzle-like extension 18 protruding down and slightly into the chamber 7 and the end of this extension is provided with axial slots 19 extending diametrically therethrough for communication with the passage 6.

30 In the operation of the invention, when the ball 17 is at rest in the bottom of the chamber 7, as shown in the drawing, it completes a circuit between the space contacts 12 and 13 to short circuit the ignition system from the coil C through the cable 14, contact 12, ball 17, contact 13, cable 15 and ground 16, and thereby cut off the engine B.

35 Upon starting, however, the starter (not shown) turns over the engine B and starts operation of the oil pressure system O to pump oil under pressure through the supply line S to the engine B. When the oil is pumped through the line S, it is forced through the passage 5 into the chamber 7 and out through the passage 6 to the engine B. The flow of the oil from the passage 5 forces the ball 17 upwardly in the chamber 7 and thereby breaking the short circuit through the contacts 12 and 13.

40 45 50 55 Obviously, therefore, if the supply of oil is sufficient in quantity to produce the pressure necessary to move the ball 17, the ball 17 will be moved upwardly in the chamber 7 and thereby break the short circuit through the contacts 12 and 13.

sary, it will lift the ball 17, cutting out the short circuit and permitting the operation of the ignition system. If however, the oil decreases in quantity to a dangerous degree, it is incapable of producing sufficient pressure to lift the ball 17, and, consequently, the ignition system is short circuited so that the engine cannot be operated. The weight of the ball 17 should be regulated in accordance with the quantity of oil required for the particular engine.

If the oil pressure is sufficient, the ball 17 may be forced upwardly against the plug 4 and might possibly close the passage 6. The extension plug 19 precludes this danger, however, having rounded edges that tend to cam the ball laterally, away from the passage 6. Furthermore, even if the ball seals the mouth of the passage, the oil may freely by-pass the ball through the slots 18. In addition, if the passage 6 is of a size that might be entered and jammed by the particular ball, one or more of the lips of the extension between the slots 18 may be bent inwardly to restrict the free opening of the passage 6.

Although a certain specific embodiment of the invention has been shown and described, it is obvious that many modifications thereof are possible. For instance, the body 2 may be formed of an insulating thermo-plastic material in which event the insulating sleeves 18 and 11 may be dispensed with. The invention, therefore, is not to be restricted except insofar as is necessitated by the prior art and by the spirit of the appended claim.

That which is claimed as new, is:

A safety switch of the type inserted within the oil pressure and ignition lines of an internal combustion engine for short circuiting the ignition line upon lack of sufficient pressure in the oil line, which switch comprises a cylindrical tube that has integral threads at both the top and bottom

ends thereof, the threads at the top being internal threads, an inlet plug threaded to the threads at the bottom of said tube and having an axial bore for admitting oil from the pressure line, an outlet plug threaded into said internal threads of the top of said tube and having an axial bore for exhausting oil to the pressure line, a metal ball of a diameter substantially larger than said bores and freely enclosed within said tube to be selectively movable against said plugs to seal the bores therein, spaced electric contacts extending inwardly from the sides and in the bottom portion of said tube to be bridged by said ball when it moves against the inlet plug and is at rest, an integral extension on the bottom of said outlet plug and depending into said tube, said extension surrounding the bore in said outlet plug and having a diameter that is smaller than the diameter of the interior of said tube, and radial slots in the bottom of said extension and extending from said plug bore to the periphery of said extension to by-pass oil around said ball when the ball is forced by oil pressure against said extension and seals the bore therein.
